UNITED STATES PATENT OFFICE.

CHARLES E. O. HAGER, OF HAGERSVILLE, CANADA.

PUZZLE.

SPECIFICATION forming part of Letters Patent No. 478,998, dated July 19, 1892.

Application filed July 25, 1891. Serial No. 401,012. (No model.)

To all whom it may concern:

Be it known that I, CHARLES EDWARD OR-
LOFF HAGER, a citizen of the Dominion of
Canada, residing at Hagersville, in the county
5 of Haldimand and Province of Ontario, Can-
ada, have invented certain new and useful
Improvements in Games or Puzzles, called
"The Pilgrim's Progress," of which the fol-
lowing is a full clear, and exact specification.

10 The object of my invention is to provide a
game to be played by one or more persons, in
which a certain amount of practice and skill
is required to cause the ball or marble em-
ployed (representing the Pilgrim) to roll into
15 the desired goal, (representing Heaven.)

In the drawings accompanying this specifi-
cation, Figure 1 is a plan view showing my
invention; and Fig. 2 is a cross-sectional view
of the same, taken on the line X X of Fig. 1.

20 A represents the board upon which the
game is played, this board having a raised
ledge B all around it to prevent the ball from
running off.

C is a slight cavity (Repentance) in the
25 board, from which the ball starts on its pil-
grimage.

D is another cavity slightly raised and
called "the Rock," into which cavity the ball
should run from C.

30 E is a raised portion called "the Bank of
Faith," having a curved edge on the side near-
est the Rock. The ball, after leaving the
Rock, strikes against this Bank E, and the ob-
ject of the player is then to cause the ball to

35 travel down the Straight and Narrow Path F
to the goal G. This Path F is made slightly
raised and rounded, forming the segment of
a circle in vertical cross-section, so as to en-
hance the difficulty of rolling the ball in a

40 straight line along its surface. It will be seen
that this rounded surface gives the ball a ten-
dency to roll off at the sides into the "Byways
of Sin," which are here represented by pas-
sages H, formed between the raised portions I

45 and I'. These passages H are formed on both
sides of the Narrow Path F and run into a pas-
sage-way called "the Road to Repentance,"
designated by the letter J, on the one side, and
into the "Broad Road of Sin" K on the other
50 side. The Byways H descend slightly away

from the Narrow Path F and are provided with
sharp declivities L L', rendering it impracti-
cable for the ball to return to the Narrow Path
after passing over these declivities. The goal
G (Heaven) is reached by traveling down the 55
Narrow Path F and is the ultimatum of the
game. This goal consists of a slightly-raised
cavity.

The Road to Repentance J, which is entered
from the Byways of Sin H on one side of the 60
Narrow Path F, is formed between raised por-
tions I' and the raised ledge B. This Road J
leads round the back of the Bank of Faith E,
and the ball should roll in this direction and
return to cavity C, (Repentance,) from whence 65
a fresh start can be made.

The Broad Road K is hollowed out through
its entire length, being deeper at one end
than at the other. The deepest end is pro-
vided with a sunken cavity M, representing 70
"Death in Sin." The ball, passing over the
declivities L' into the Broad Road K, will natu-
rally tend to roll right down into the cavity
M, and some skill is required to prevent it
from rolling in that direction. 75

The object of the game is to prevent the
ball from rolling into cavity M, and instead
to cause it to roll back into cavity C, from
whence a fresh start can be made.

Two or more balls should be used in this 80
game, and when a ball falls into the cavity
M it is considered to be out of the game.

The winning ball is the one which is suc-
cessful in getting into the cavity G first.

Having now described my invention, I de- 85
clare that what I claim is—

In a game-board, the cavities C, D, G, and
M, raised portions E, I, and I', rounded Nar-
row Pathway F, sunken Broad Road K, side
passages H, with declivities L and L', passage- 90
way J, and raised ledge B, as described and
shown.

In testimony that I claim the foregoing I
have hereunto set my hand this 10th day of
July, 1891.

C. E. O. HAGER.
